TABLE TOP

Phillip H. Cruikshank, Monticello, Ill., assignor
to Tylac Company, Monticello, Ill., a corpora-
tion of Illinois

Application October 13, 1931, Serial No. 568,646

1 Claim. (Cl. 41—22)

My invention relates to tables, desks, dressers, counters, and in fact, to any construction where a sanitary and water and acid proof top is necessary.

5 Primarily, the invention contemplates a loose or supernumerary top which will take the place of plate glass and other expedients which have been employed as detachable tops for dining tables, tea tables, card tables, desks, dressers, 10 soda fountain counters, and other instances where recourse has been had to either the glass top or similar expedients.

A particular object of the invention is to provide a detachable top which will be water repellent and resist the action of acids and alkali and which will also possess the property of being substantially abrasion and temperature proof.

20 A further object of the invention is to provide an article of this character which will have any desired decorative effect and which will be capable of manufacture in various sizes to accommodate the tops of furniture and other structures now in use.

25 Referring to the drawing, Figure 1 is a perspective view of a table with my top applied; Figure 2 is a detail view of the top showing its structure and a conventional decoration; Figure 3 is a sectional view; and

30 Figure 4 is a sectional view of a modification. Referring to the drawing, I have indicated my invention applied to a conventional table and the detachable top constructed in accordance with this invention is indicated at 10 and has 35 the usual edges or flanges 11.

The undersurface of the top is preferably provided with some non-abradant material, as for example, a layer of felt 12 which is adhesively united to the base 13 of the top.

40 The base 13 of the top is preferably formed of a fibrous material such as wood fiber, paper pulp, corn stalks, cane stalks, or any composition embodying two or more of the foregoing. I may also employ a product made by the Masonite company and called "Presswood" which is a fibrous material.

45 The base 13 possesses the characteristics of flexibility and plasticity and is moisture repellent. Furthermore, it is insulating and substantially inert with respect to extremes of heat and cold so that it will be temperature resistant for all ordinary purposes. This material is further characterized by great tensile strength and is resistant to abrasion. In addition, the fibrous material which I employ is substantially

free of volatiles within a normal range of temperatures, so that no perceptible or objectionable odors will be created.

As stated, the base 13 is moisture repellent, that is to say, it may be inherently water proof or some suitable water proofing agent may be employed. This water proofing agent will preferably have a high point of volatilization so that under no circumstances will any objectionable odors be created.

5 The base 13, in addition to its flexible and plastic properties, is, however, sufficiently rigid to enable it to be satisfactorily worked, that is to say, cut into strips and suitably mitered or beveled, or its contour arranged as required. Thus, with various articles to which the top is applied, the contour assumes a variety of shapes and this can be easily cared for with the present invention by sawing or compressing the material to the desired configuration.

10 The fibrous base 13 is first preferably sanded to smoothness and has applied thereto one or more coats of a suitable priming material having a high point of volatilization and which is substantially free from any objectionable odors should some of the material become vaporized.

15 For the purpose of the priming material, I employ lacquer, paint, enamel, or varnish which may be either an oil base or what is termed in the trade, a synthetic resinous enamel. Such material will be substantially water proof, plastic and flexible when it is dried.

20 It will also have the characteristic of being abrasion resistant, and which, as stated, will not volatilize at normal temperatures and in any event, will possess no objectionable odor.

25 In referring to a synthetic resinous material which I preferably employ, I mean those coatings containing synthetic resins which are condensates from phenol and a member of the aldehyde family, for example, a synthetic resin produced as a condensation product from phenol and formaldehyde.

30 Coatings of this character are available which are alkaline, acid, and neutral, and I preferably employ one which will be substantially acid and alkali resistant, according to the use to which the product must conform. In preparing the coating, the synthetic resin is dissolved by a solvent of either the ethyl, butyl, or methyl family, depending upon whether the material is to be used for air drying or oven baking and the quickness with which the varnish must dry. I preferably employ also in the coating, a plasticizer to permit the coating to expand and con-

tract so that it will conform in general with the characteristics of the base 13.

Over the priming coat there is produced a decorative effect by the use of a coating in a proper color, a decalcomania motif, or a veneer. These will be later described in detail.

At this point, however, it should be stated that where a color, tint, or hue is employed, the pigments or other ingredients for this purpose are ground to fineness, mixed with a required percentage of nitro-cellulose, whereupon the mixture is reduced to the proper viscosity by addition of a suitable solvent or carrier such as ethyl acetate.

In carrying out the invention, the base 13, after appropriate sanding to smoothness, has applied to it a priming coat, whose principal ingredient is one of the materials above described, and preferably a synthetic resin of the polybasic acid type.

At this point, it should be stated that the various coatings will be substantially acid and alkali proof and will react with the material of the base to strengthen the same to produce a very strong adhesion without, however, raising the grain of the material of the base.

The priming coat is then preferably sanded to smoothness and if required, a second priming coat of the same material is applied. This coating is likewise sanded to smoothness and thereafter the product is subjected to suitable decorative steps.

As one means of decoration, after the priming coat or coats are dried, there is applied a spray coat of a synthetic resinous material containing the desired color or combination thereof. When this is sufficiently dry, a second coat of similar material is applied and when the latter has dried, the finished coat is lightly sanded and then buffed to a high luster with any suitable means, for example, a felt pad with rotten-stone and oil.

A final polishing with a fast rotating disc of lambs wool will add to the luster and brilliancy obtained.

It will be understood that each of the priming and finishing coats will be flexible and plastic, as well as moisture and temperature resistant. This coating, moreover, will, within normal temperatures, be stable and free from possibilities of volatilization so that no objectionable or perceptible odors will be given off. In addition, the top will be resistant to acids and alkalies and the ornamental features which may be employed will retain their natural appearance and not deteriorate by reason of wear.

By the use of the several coatings as herein described, a nice finish will be made available which can be varied at will.

At this point, it should also be stated that the

loose and removable top will not only have its top surface treated in the above described manner, but the edges or flange portions will likewise be similarly coated.

I may apply to either the priming coat or the colored finishing coat by means of a varnish glue, a decalcomania of appropriate design and contrasting color to produce various motifs such as a center design, borders, and corner pieces. After the decalcomania has set, and becomes thoroughly dry, it is coated with a sealer coating of shellac and varnish, after which a coat of clear buffing lacquer enamel containing a synthetic resin is flowed as the final finishing coat to protect the ornamentation and withstand wear and abuse. Such finishing coatings will be alkali and acid resistant, moisture repellent and substantially temperature proof. Furthermore, they will be free from any objectionable odor and will impart a nice finish to the final article.

After the final clear coating has thoroughly dried, it may be buffed and polished as heretofore described.

In lieu of the decalcomania effect, I may substitute decorations comprising silver, bronze, copper, or aluminum leaf in various designs, as well as reproductions of the various kinds and colors of marbles and also photoengravure representations.

I may also utilize a wood veneer from 1/75" to 1/120" in thickness of natural woods, both domestic and foreign. Such veneer may obviously carry any desired grain or decoration and will be suitably finished by the use of a sealer coat and a clear finishing coat.

Referring to the drawing, I have indicated the priming coat at 14 and the decorative coating at 15 in Figure 3. In Figure 4 I have indicated at 16 the decalcomania or veneer or other effect as described.

The present invention comprises a product in which all of the materials will not possess a perceptible or objectionable odor, wherein they are substantially water proof and abrasion proof. Furthermore, the coatings which are applied over the fibrous base are wear resistant, inert to the action of acids and alkalies and possess the necessary plasticity and flexibility so that there can be no opportunity for cracking or otherwise marring the finish.

I claim:

A table top adapted to be loosely disposed upon tables and similar articles, comprising a base of pressed fibrous material having a protective layer of synthetic resin on one surface, a decorative design comprising metallic leaf enclosed by said layer, and a layer of non-abrasive material affixed to the opposite surface.

PHILLIP H. CRUIKSHANK.
